UNITED STATES PATENT OFFICE

147,801

DESIGN FOR A PAIR OF SCISSORS

Cyril Larocque, Baltimore, Md.

Application January 5, 1946, Serial No. 125,302

Term of patent 3½ years

(Cl. D22—5)

To all whom it may concern:

Be it known that I, Cyril Larocque, a citizen of the United States, residing at Baltimore and State of Maryland, have invented a new, original, and ornamental Design for a Pair of Scissors, of which the following is a specification, reference being had to the accompanying drawing, forming part thereof.

The Figure 1 is a plan view of a pair of scissors, showing my new design, and

The Figure 2 is a side elevation of Figure 1.

I claim:

The ornamental design for a pair of scissors, as shown.

CYRIL LAROCQUE.
